DISPLAY CARD FOR A CHILD'S DENTAL KIT

Helen R. Blumberg, 1231 Barrowdale Road, Rydal, Pa.

Filed Oct. 14, 1963, Ser. No. 76,972

Term of patent 14 years

(Cl. D80—5)

FIG. 1 is a front elevational view of a display card for a child's dental kit showing my new design, the rear being substantially plain and unornamented;

FIG. 2 is an elevational view taken from the right of FIG. 1; and

FIG. 3 is a top plan view thereof.

I claim:

The ornamental design for a display card for a child's dental kit, as shown and described.
